UNITED STATES PATENT OFFICE.

PONTUS OSTENBERG, OF SAN JOSE, CALIFORNIA.

CENTRIFUGAL PUMP.

1,273,913.

Specification of Letters Patent. Patented July 30, 1918.

Application filed March 15, 1917. Serial No. 155,020.

To all whom it may concern:

Be it known that I, PONTUS OSTENBERG, a citizen of the United States, and resident of San Jose, in the county of Santa Clara and State of California, have invented certain new and useful Improvements in Centrifugal Pumps, of which the following is a specification.

My invention relates to improvements in centrifugal pumps which utilize two or more stages of rotors to revolve liquid to create pressure, of which the chief characteristic feature is the elimination of bearings and necks between the rotors or impellers, and in inserting the rotors in a continuous spiraled tubular pump body, as will be more fully described herein.

Another feature of the invention is that the liquid will be kept in a continuous revolving motion from the time it enters the first rotor or impeller member until it leaves the last member, which is an essential point in high operating efficiency.

One object of the present invention is to provide a simple, substantial, cheaply manufactured deep well pump, and particularly to provide a novel construction of pump body or bowl and impeller arrangement conducive to high operating efficiency, which will be more fully described herein.

In the drawings,—

Figure 1 is a vertical, transverse section through my improved pump, partly in elevation.

Fig. 2 is a sectional view on line A—A of Fig. 1 but provided with vanes extending back to the body of the rotor.

Fig. 3 is an elevation of one of the vanes shown in Fig. 2 and a section through the parts connected thereto.

Fig. 4 is a section-elevation of a horizontal pump embodying my improvements.

Fig. 5 is a sectional view through a modified form of vane.

Fig. 6 is a sectional view on line B—B of Fig. 3.

Similar characters of reference refer to similar parts throughout the several views.

At 1 I have shown a tubular pump body or bowl connected at its upper end to discharge casing 2 and provided with three

chambers 3. In vertical cross-section each chamber wall is shown as curving sharply inwardly at the bottom and having a more gradual outward curve at the top to the upper edge 4. Within each of said chambers 3 are formed three spiral members 5, each member extending a distance around chamber 3, rising from the lower curve of said chamber in such a manner as to form a continuous surface therewith as at 5^a, and gradually narrowing and dying out as it reaches upper edge 4 and shown at 5^b.

At 6 is shown a rotor member secured to shaft 7 by key 8, rotor 6 being formed to present a circular flange 9 to the under side of the outer portion of which is secured a number of vanes as 10, said vanes 10 being secured in turn to an annular member 11 and each vane being provided with a vertical wearing surface curving backwardly with respect to a diametrical plane passing through its inner edge. In Fig. 1 vanes 10 do not extend back to the body of the rotor as shown in Fig. 2 but only extend back the width of member 11. Member 11 is preferably beveled on its under side to form a continuation of the inwardly curving upper portion of chamber 3. Since the rotors 6 are designed to be axially aligned and operated as one member, thereby forming a compound rotor, the under surface of each flange is curved inwardly and downwardly as at 12 to meet the inward and upward curve 13 of the next lower rotor so that the upper and lower surfaces of the vanes form a continuous surface with the abutting surfaces of the contiguous members. The lowermost rotor 6 is preferably formed with a flat under surface to flange 9 as shown at 14.

When formed and fitted as above set forth, with the upper surfaces of members 11 in alignment with the lower curve of chambers 3, a continuous curved passage is formed from the bottom of bowl 1 to the discharge casing 2. The several rotors 6 are secured to shaft 7 as described and therefore have no bearings or necks such as usually provided, shaft 7 operating in bearing 15 which is supported in the usual manner. On the lower portion of bearing 15 is formed a flange 16 having a downwardly

turned edge 17 formed thereon to loosely engage the outer and upper portion of the upper rotor member 6 thereby providing a chamber 18 between said rotor member 6 and flange 16. At 19 I have provided a chamber in the lower end of shaft 7, the same being connected to chamber 18 by one or more conduits as 20.

Rotor vanes 10 are shown and each preferably positioned in such a manner as to present a wearing surface curved backwardly with respect to a diametrical plane passing through its inner edge as in Fig. 2, and at the same time curving forwardly and downwardly as shown in Figs. 2, 3 and 6. In Fig. 5 another form of vane is shown which not only curves backwardly as shown in Fig. 2 but also inclines downwardly and forwardly in straight lines. When the form used in Fig. 6 is used it is preferable to carry the vane clear back to the curved body of member 6, as shown. Fig. 4 indicates that my improved form of pump is also readily adaptable to the horizontal turbine the general direction of the spiral members being indicated in dotted lines at 5°.

When in operation shaft 7 is revolved in the direction indicated by the arrow in Fig. 2, the water being thrown outwardly and given a rotary movement by the force imparted through vanes 10. As the water is forced into chambers 3 it is received by the upwardly curving spiral members 5 and guided upwardly until taken up by the next succeeding rotor or forced into the discharge casing as the case may be. The members 5 may be of any desired number and of any desired pitch, their function being solely to assist in directing the water upwardly and thereby lessening the inertia which the vanes themselves have to overcome.

It may now be seen that my improved pump provides a construction which does not require bearings in connection with each rotor, the several members 6 being contiguously positioned and forming a compound rotor, consequently a multi-stage type of pump of the character above described is compact and durable. This form of pump permits the various surfaces where friction may occur to wear away considerably without affecting the efficiency of the pump.

It is understood, of course, that I do not wish to confine myself to the specific form and construction above described, as various changes may be made to meet the requirements of practical application and exigencies of manufacture, but within the scope of the appended claims. In the following claims the words "inserted therein in a unitary structure" are used in the sense of being a unitary structure when in position and not necessarily being a unitary structure during the act of placing in position. For instance, if the shaft were put in position

in the casing and the several rotors subsequently placed thereon they would form a unitary structure inserted within the casing and would be removable in a unitary structure.

Having thus described my invention, what I claim as new and desire to secure by Letters Patent, is:—

1. In a centrifugal pump, a casing provided with a cylindrical central chamber having a plurality of rotors operatively and removably insertible therein in a unitary structure, and having inlet and outlet openings, and an annular chamber formed in the wall thereof in operative relation to each rotor, 75 each annular chamber having one or more upwardly 80 inclined vanes positioned therein.

2. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein. 85

3. A centrifugal pump comprising a multichambered casing having a compound rotor removably and operatively insertible therein in a unitary structure. 90

4. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber curving sharply inwardly at the bottom and more gradually outwardly at the top, and having one or more upwardly inclined vanes positioned therein. 95

5. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber curving sharply inwardly at the bottom and more gradually outwardly at the top and having one or more upwardly inclined vanes positioned therein, each vane forming a continuous surface with its respective chamber at its lower end. 110

6. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber curving sharply inwardly at the bottom and more gradually outwardly at the top and having one or more upwardly inclined vanes positioned therein, each vane forming a continuous surface with its re- 115

- spective chamber at its lower end, gradually becoming narrower as it approaches the upper edge of said chamber and inwardly inclined toward the axis of said chamber.
5. 7. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber curving sharply inwardly at the bottom and more gradually outwardly at the top and having one or more upwardly inclined vanes positioned therein, each vane forming a continuous surface with its respective chamber at its lower end and gradually becoming narrower as it approaches the upper edge of said chamber.
10. 15. 8. In a centrifugal pump, a shaft, two or more rotors mounted thereon, a common bearing for said rotors, and a pump bowl provided with a plurality of spiraled chambers operatively positioned with relation to said compound rotor.
15. 9. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein, and each vane forming a continuous surface with its respective chamber at its lower end.
20. 10. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein, each vane forming a continuous surface with its respective chamber at its lower end and gradually becoming narrower as it approaches the upper edge of said chamber.
25. 15. 11. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein, each vane forming a continuous surface with its respective chamber at its lower end and gradually becoming narrower as it approaches the upper edge of said chamber and inclining inwardly toward the axis of said chamber.
30. 16. 12. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein, each vane becoming narrower as it approaches the upper edge of said chamber.
35. 17. 13. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein, each vane becoming narrower as it approaches the upper edge of said chamber and being inclined inwardly toward the axis of said chamber.
40. 18. 14. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein, each vane being inwardly inclined toward the axis of the chamber.
45. 19. 15. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, said rotors being centered by a bearing positioned above the uppermost rotor.
50. 20. 16. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, the lower portion of each of the vanes of said rotors curving forwardly in the direction of rotation of said rotors.
55. 21. 17. In a centrifugal pump, a casing provided with a cylindrical central chamber having a plurality of rotors operatively insertible therein in a unitary structure, and having inlet and outlet openings, and an annular chamber formed in the wall thereof in operative relation to each rotor, each annular chamber having one or more upwardly inclined vanes positioned therein, and the lower portion of each of the vanes of said rotors curving forwardly in the direction of rotation of said rotors.

18. In a centrifugal pump, a casing provided with a cylindrical central chamber having a plurality of rotors operatively inserted therein in a unitary structure, and 5 having inlet and outlet openings, and an annular chamber formed in the wall thereof in operative relation to each rotor, the upper

and lower surfaces of said rotors forming a continuous surface with the abutting surfaces of the contiguous members.

10

In testimony whereof I have hereunto affixed my signature this 7th day of March, 1917.

PONTUS OSTENBERG.
